UNITED STATES PATENT OFFICE.

EUGENE LEVAY, OF NEW YORK, N. Y.

DESIGN FOR A HOB FOR A QUOIT GAME.

Application filed July 13, 1925. Serial No. 14,063. Term of patent 14 years.

To all whom it may concern:

Be it known that I, EUGENE LEVAY, a citizen of the United States, residing in New York, New York, have invented a new, original, and ornamental Design for a Hob for a Quoit Game, of which the following is a specification, reference being had to the accompanying drawing, forming part thereof, in which the figure is a perspective view of a hob for a quoit game.

I claim:

The ornamental design for a hob for a quoit game, as shown.

EUGENE LEVAY.
